METHOD OF MAKING OIL HOLE TWIST DRILLS

Stuart A. Cogsdill, Detroit, Mich., assignor to
Cogsdill Twist Drill Co., Detroit, Mich., a corporation of Michigan

Application December 7, 1942, Serial No. 468,061

6 Claims. (Cl. 76—108)

This invention relates to twist drills and particularly to twist drills having a liquid passage extending from the shank end thereof to the point end thereof for the purpose of introducing a flow of coolant or lubricating liquid to the cutting edge of the drill during a drilling operation, the principal object being the provision of an improved method of making such drills in an efficient and economical manner.

Objects of the invention include the provision of a method of making oil hole twist drills including the step of forming a longitudinally extending groove in a surface of a blank therefor and lips or ridges along each side of such groove, then working said lips or ridges toward and into sealing engagement with each other whereby to close the open side of said groove and thereby form a hole in said blank; the provision of a method as above described in which the surface of said blank is provided with a shallow but wider groove therein having a side wall disposed circumferentially outwardly of said lips or beads and forming a guide for the tool employed in working said lips or beads together to close the first-mentioned groove; and the provision of a method of making oil hole drills as above described in which the depth of the second groove is substantially equal to the amount of clearance desired back of each trailing edge of the associated flute of the drill.

Further objects of the invention include the provision of a method of making oil hole twist drills comprising forming a straight and longitudinally extending groove in the surface of a cylindrical drill blank, closing the open side of the groove by working the metal of the blank on either side thereof into contacting relationship along the center of the groove, and thereafter twisting the blank into spiral conformation; the provision of a method of making an oil hole twist drill as above described in which the groove is closed before the flutes are machined in the blank and the flutes are machined in parallel relation to the grooves in the blank; and the provision of a method of making an oil hole twist drill in which the groove or grooves which is or are to ultimately form the oil hole or holes in the drill are formed and fully completed in a straight condition and before the flutes are formed in the drill blanks.

The above being among the objects of the present invention, the same consists in certain novel steps and combination of steps of operation in the formation of an oil hole twist drill to be hereinafter described with reference to the ac-

companying drawing, and then claimed, having the above and other objects in view.

In the accompanying drawing which illustrates suitable steps of operation in the manufacture of an oil hole twist drill in accordance with the preferred practice of the present invention, together with a drill constructed in accordance with the present invention, and in which like numerals refer to like parts throughout the several differ-

ent views,

Fig. 1 is a side elevational view of a drill blank in partially completed condition;

Fig. 2 is an enlarged transverse, sectional view taken on the line 2—2 of Fig. 1, and illustrating the type of tool preferably employed for forming the grooves in the blank, which grooves are later to be converted into oil holes;

Fig. 3 is a fragmentary, sectional view taken diametrically through the upper end of the drill blank shown in Fig. 1 to illustrate the bore therein and the passages connecting it to the grooves which are later formed into the oil holes;

Fig. 4 is a view similar to Fig. 2 but illustrating a machining operation upon the blank to form lips or beads along each side of the groove and which operation, as hereinafter brought out, may if desired be accomplished simultaneously with the operation disclosed in Fig. 2;

Fig. 5 is a view similar to Figs. 2 and 4, but illustrating the operation of closing the outer side of the grooves to form the oil holes;

Fig. 6 is a transverse, sectional view through the drill blank illustrating a step of operation thereon following the closing of the grooves therein;

Fig. 7 is a view similar to Fig. 6 but illustrating the operation on the drill blank following that shown in Fig. 6; and,

Fig. 8 is a side elevational view of the completed drill.

In my prior United States Letters Patent No. 2,148,805, issued February 28, 1939, on Method of making oil hole drills, a method of making such drills is disclosed in which grooves are machined

in the lands of the drill at the same spiral as the flutes thereof and thereafter the metal of the lands on each side of each of such grooves is worked inwardly to close the open side of such grooves, thereby to form so-called oil holes or passages through which lubricant, suitable coolant or other fluid, may be fed to the point of the drill for well-known reasons.

Since the issuance of said patent, experience has shown that particularly with the high speed steels employed in modern drill manufacture, the

method there disclosed for closing the open sides of the grooves while possible, was commercially inadequate in that the working of the metal over the open side of the groove was too difficult and too often resulted in an imperfect closure of the open side of the groove. In accordance with one phase of the present invention, I have discovered that the closure of the open side of such groove may be greatly facilitated and the occasional imperfect closure of the groove in the former case be eliminated if an upstanding bead or lip is formed at each side of the groove at the open side thereof and is then operated upon to work it inwardly toward the center of the groove, as by an operation something akin to a bending operation instead of a true metal flowing operation as in the case of my prior patent, until the beads or lips at opposite sides of each groove are brought into contacting and sealing relation with respect to each other. The formation of these lips or beads at opposite sides of each groove provide a construction in which the metal constituting the same may be readily displaced inwardly to close the open side of the groove in a much easier and efficient manner than that suggested in my prior patent and with materially less force required in the closing operation.

In the broader aspects of the present invention, the formation of these lips or beads along each side of the groove which is to form an oil hole may be provided regardless of whether the groove is formed straight, that is, in axially parallel relation with respect to the axis of the drill and the drill blank thereafter twisted to the desired spiral conformation, or whether it is formed in the spiral manner illustrated in my prior patent. However, in accordance with a further phase of the present invention, such grooves, as well as the flutes, are formed in the blanks straight, that is, all lying in a single plane parallel to the axis of the drill blank, the groove closed, and thereafter the blank twisted to the desired spiral conformation.

Furthermore, while such grooves may be formed in the blanks after the flutes have been formed therein, the grooves are preferably formed in the blank and closed prior to the formation of the flutes. The reason for so forming the grooves and closing them at least described is because in actual practice in the formation of oil hole drills as disclosed in my prior patent above identified, it was found that the closing operation, that is, the displacing of metal inwardly from the open sides of the grooves closed such open sides, was extremely difficult when the grooves were already of spiral conformation, for the reason that the blank had a tendency to slip sideways, or axially of the rolls employed in the closing operation, and that when such slippage occurred an unequal displacement of the metal on opposite sides of the grooves occurred and often resulted in an imperfect closure of the open side of the groove. In accordance with this further phase of the present invention, I have discovered that if the grooves are straight and particularly if they are closed prior to the formation of the flutes in the drill blanks, the drill blank may be more accurately and easily guided between the rolls employed for working the metal over the open sides thereof, the blank is better able to withstand distortion under the force of the closing rolls, and such closure may be accomplished in

a quicker, more economical and more efficient manner, resulting in a more perfect product.

Although, as above described, the provision of the lips or beads along each side of the grooves which are to form the oil holes in the finished product is applicable to the manufacture of such oil hole drills whether such grooves are formed in the drill blank at the spiral required in the finished product, or are formed straight and thereafter the blank is twisted to the desired spiral conformation, and although the flutes in the drill may be initially formed of the desired spiral conformation desired in the finished product, or may be formed straight and the blank thereafter twisted to bring the flutes to the desired spiral conformation, for the purpose of illustration the preferred method is illustrated in the accompanying drawing as being that in which both the grooves and the flutes are formed straight in the blank and the blank thereafter twisted to bring the flutes to their desired spiral conformation. Also, although the grooves may be closed either before or after the flutes are formed in the drill blank, as a matter of illustration the steps of operation illustrated in the accompanying drawing are those in which the groove is closed prior to the formation of the flutes as this is the preferred practice in accordance with the present invention.

Additionally, although the grooves and the lips bounding the opposite sides of the same may be formed simultaneously in a single machining operation, for the purpose of clarity in description in the accompanying drawing the groove and the lips are shown as being formed by independent machining operations. It will, therefore, be understood that the showing in the drawing and the following explanation of the same is that of the preferred method of making oil hole twist drills in accordance with the present invention, but that the variations in manufacturing procedure above outlined are within the scope of the present invention and are covered herein where the language of the claims permits.

Referring now to the accompanying drawing, and particularly to Fig. 1, the drill blank there shown comprises a main body portion 10 and a shank portion 12, the latter here shown as of cylindrical conformation for the purpose of illustration, the two being joined by a neck portion 14 of slightly reduced diameter in accordance with conventional practice. Where such drill blank is to form a so-called high speed drill, it will be appreciated that the body 10 may be formed of such high speed steel and the shank portion 12 formed from a lower grade, less expensive and usually softer steel, the two being joined in the area of the neck 14, this being in accordance with conventional practice. It will also be understood that the particular drill blank shown in Fig. 1 is originally made under such conditions from two cylindrical sections of steel which are welded together in the area of the neck 14 and thereafter turned to an outside diameter slightly larger than that desired in the final product.

The particular drill and blank shown in the drawing is assumed, for the purpose of illustration, to be a two-flute drill and, accordingly, the drill blank shown in Fig. 1 is provided on diametrically opposite sides thereof with a groove 16 formed in its outer periphery, such groove being straight, parallel to the axis of the drill blank, and extending from the free end of the main body portion 10 to a point adjacent to but short

of the neck 14. While the grooves 16 may be formed in the blank in any suitable manner, they are preferably machined therein and the machining operation preferably employed is a milling operation, such as is illustrated in Fig. 2 in which a milling cutter 18 of a width corresponding to the width desired in the groove 16 and preferably having a peripheral cross-section of semi-circular conformation, and carried upon a suitable arbor such as 20, is rotated and simultaneously fed axially of the drill blank with the cutter 18 imbedded to the desired depth in the surface thereof.

In order to conduct fluid to the oil holes in the drill, the shank 12, as best illustrated in Fig. 3, is provided with an axial bore 22 therein which leads from its free end through the neck 14 and down into the body 10, and a passage 24 is drilled through the metal between the bottom of each groove 16 and the bore 22, so as to communicate the bore 22 with the grooves 16 and therefor with the oil holes which are eventually to be formed in the drill.

The next operation performed on the blanks in accordance with the particular embodiment of the invention disclosed in the drawing is the formation of a lip or bead 26 along each edge of each groove 16 at the open side thereof. These lips or beads 26 form a portion of the side walls of the corresponding groove 16 along the open sides of such grooves. In the broader aspects of the invention, they may be formed in any suitable manner, but it is preferred to form them by a milling operation, and such operation is, therefore, disclosed in Fig. 4. In the particular case shown, it is accomplished by the use of a milling cutter 28 having peripheral cutting edges of inverted V-like conformation as shown, and in the milling operation the cutter 28 is centrally arranged with respect to a plane including the axis of the blank and the center of the corresponding groove 16. While the amount of V of the cutting edges of the milling cutter may vary so as to provide the lips or beads 26 of any desired radial dimension or depth, preferably the depth of the V is such that when the milling cutter is imbedded in the work the desired distance, the depth of the supplementary groove 30 thus cut by the milling cutter 28 and disposed centrally of the corresponding groove 16, as disclosed in the lower portion of Fig. 4, is of substantially the same depth as the clearance preferably provided back of the trailing edge of each flute, as indicated in Fig. 7, and which will hereafter be discussed in greater detail. Also, the sides of the milling cutter 28 are preferably perpendicular to its axis of rotation so that the sides of the supplementary groove 30 are straight and parallel to each other and to the central plane of the cutter 28.

Although the flutes of the drill may now be milled or otherwise formed in the blank, I prefer, as above stated, to close the groove 16 before such flutes are formed therein, and, accordingly, in the drawing the next step, which is illustrated in Fig. 5, comprises closing the lips 26 over the outer sides of the grooves 16 to produce the oil holes 32 desired in the finished product. While this may be accomplished in any suitable manner in accordance with the broader aspects of the present invention, it is preferably accomplished by means of apparatus such as illustrated in Fig. 5. This comprises a pair of rolls 34 of a rim width such as to be relatively closely but slidably received between the opposite side walls of the supplementary grooves 30. The peripheries

of the rolls 34 are preferably dished or concave to such an extent as to be complementary to the periphery of the portion of the drill body following the trailing edge of the flute and forming a clearance therefor. In practice, the rolls 34 are mounted upon suitable arbors 35, they are preferably driven in synchronism with each other, and the blank is reciprocated between them while the rolls 30 are gradually drawn toward one another. During this operation, the peripheries of the rolls 34 acting upon the lips 26 draw the lips 26 on each side of each groove 16 toward one another, more or less in the nature of a bending operation, until the tips or free edges of the lips or beads 26 are forcibly brought into contact with each other with such firmness as to effectively seal the joints between them, as brought out in Fig. 5. This operation as above explained and as shown in Fig. 5, completes the formation of the oil holes 32.

The rolls 30, in fitting between the side walls of their corresponding supplementary grooves 30, cooperate with such side walls to hold the drill blank centrally between them and effectively prevent any sidewise slippage of the blank during this operation, thus overcoming one of the difficulties experienced in carrying out the closing of the grooves in my prior patent above identified. Nevertheless, if desired, guiding rolls 33 may be disposed at each side of the blank during the operation disclosed in Fig. 5 to insure the central relation of the blank with respect to the rolls. It will be appreciated that the rolls 33 will cooperate with the blank better if, as shown, the flutes have not yet been formed in the blank.

The next operation, in accordance with the particular sequence or steps illustrated in the drawing, is the operation of forming flutes 36 in the main body portion 10. These flutes may be formed in a conventional operation, that is, by a milling operation, and in the particular case shown are formed straight and parallel with the oil holes 32 and, of course, circumferentially outside of the area in which the oil holes 22 have been formed.

Following the operation of forming the flutes 36, and where the drill is to be provided with a peripheral relief or clearance following the trailing edges of the flutes 36, such clearance which is illustrated in Fig. 7 at 38 is then provided in any suitable way, such, for instance, by a milling operation in accordance with conventional practice. In view of the fact that the peripheries of the rollers 34 are preferably formed complementary to the curvature of the relieved surfaces 38 and the rolls 34 in the operation illustrated in Fig. 5 are imbedded into the surface of the main body portion 10 a distance equivalent to the relief 38 desired, it will be appreciated that the bottom of the grooves formed in the main body portion 10 by the rolls 34 thus form a portion of the relieved surfaces 38.

The next step of operation, in accordance with the particular sequence of operation disclosed in the drawing, is the twisting of the blank thus formed to bring the main body portion 10 thereof and the flutes 36 therein into spiral conformation, and this may be done in any suitable or conventional manner, with the result that the blanks will then assume the condition illustrated in Fig. 8. After the blank has reached the condition illustrated in Fig. 8, if deemed necessary or desirable the flutes 36 may be finish machined to bring them to the desired true helical conformation, cross-sectional configuration, and high state of finish, or the flutes may be left in

their as twisted condition if such added operation is not thought necessary. The drill may then be hardened in accordance with conventional practice, ground and sharpened to bring it to its final condition.

Having thus described my invention, what I claim by Letters Patent is:

1. In the manufacture of an oil hole twist drill from a cylindrical blank, the steps of forming a pair of longitudinally extending grooves in an exterior surface of said blank, one of said grooves being deeper and narrower than the other and said other of said grooves being disposed equally on both sides thereof and shaped to form a bead along each side of the first-mentioned groove, and then simultaneously operating upon said beads to displace them toward one another and into contacting and sealing engagement with respect to each other whereby to close the outer side of said first-mentioned groove.

2. In the manufacture of an oil hole twist drill by the use of a forming roll, the steps of forming a longitudinally extending groove in the surface of a cylindrical drill blank, forming a second groove in said surface of said drill blank centrally aligned with the first-mentioned groove and disposed substantially equally on opposite sides thereof, the width of said second groove being approximately equal to the thickness of said forming roll, and pressing said roll radially into the surface of said drill blank and effecting relative travel of said roll longitudinally of said blank while guided between the sides of said second groove thereby to displace the metal of said blank towards the center of said first-mentioned groove to close the open side thereof without closing the bottom portion thereof.

3. In the manufacture of an oil hole drill from a cylindrical blank by the use of a forming roll, the steps of forming a longitudinally extending groove in the exterior surface of said blank, said groove having a radially outer portion of greater width than the inner portion thereof and a radially outwardly extending lip along the junction of each side wall of the narrow portion of said groove and the bottom wall of the widened portion thereof, said widened portion being substantially the same width as the thickness of said forming roll, and then pressing said forming roll radially inwardly of said blank in contact with said lips while guided between the side walls of said wide portion of said groove, thereby displacing said lips toward the center line of the narrow portion of said groove to close the open side of the narrow portion.

4. In the manufacture of an oil hole drill from a cylindrical metal blank by the use of a pair of metal displacing rollers, the steps of forming a pair of longitudinally extending grooves in an exterior surface of said blank on diametrically opposite sides thereof, forming a pair of second grooves in said blank each centrally of the corresponding of said first-mentioned grooves and disposed equally on either side thereof, of less depth than the first-mentioned grooves of a width substantially corresponding with the width of said rolls, and of a bottom shape to provide a lip extending along each side of the first-mentioned grooves at the open sides thereof, gripping said blank between said rolls with said rolls received in and guided between the side walls of the cooperating of said second-mentioned grooves, and effecting relative longitudinal movement of said blank between said rolls and simultaneously pressing said rolls toward each other and into said blank to displace said lips toward and into contact with each other to close the open side of the first-mentioned grooves without closing the bottom portions thereof.

5. The method of forming an oil hole in a drill body which comprises providing a cylindrical drill blank, cutting a longitudinal grooved portion in the external surface of the blank, cutting an intermediate groove between opposite edges of the grooved portion and forming upstanding lips or beads along opposite edges of the intermediate groove, and then deforming the lips or beads toward and into contacting relation with respect to each other so as to substantially close the open side of the intermediate groove.

6. In the manufacturing of an oil hole twist drill by the use of a forming roll, the steps of forming a longitudinally extending groove in a surface of a cylindrical drill blank, forming an additional groove of lesser depth in said blank on each side of and in parallel relationship with respect to the first-mentioned groove so as to provide a radially extending lip between the first-mentioned groove and each of the second-mentioned grooves, then positioning said roll centrally of the first-mentioned groove and pressing it radially into the surface of said drill blank and effecting relative travel of said roll longitudinally of said blank whereby to bend said lips toward and into contacting relationship with respect to each other without closing the bottom of the first-mentioned groove.

STUART A. COGSDILL.
